HOUSING FOR POWER SWEEPER

Ralph C. Peabody, Brooklyn Center, and John N. Polivka, Hopkins, Minn., assignors to Tennant Company, Minneapolis, Minn.

Filed Mar. 16, 1973, Ser. No. 341,974

Term of patent 14 years

Int. Cl. D12—13

U.S. Cl. D49—9.1

Fig. 1

Fig. 2

Fig. 3

Fig. 4

Fig. 5

Fig. 6

Fig. 7

Fig. 8

Fig. 9

FIG. 1 is a front perspective view of a housing for a power sweeper showing our new design;

FIG. 2 is a front perspective view of a second embodiment thereof;

FIG. 3 is a right side elevational view of the housing for a power sweeper disclosed in FIG. 1;

FIG. 4 is a left side elevational view thereof;

FIG. 5 is a left side elevational view of the second embodiment thereof, the right side being identical thereto;

FIG. 6 is a rear elevational view of both embodiments;

FIG. 7 is a front elevational view of the housing for a power sweeper disclosed in FIG. 1;

FIG. 8 is a top plan view thereof; and

FIG. 9 is a bottom plan view of both embodiments.

The broken line disclosure of the motor elements is for illustrative purposes only and forms no part of the claim design.

We claim:

The ornamental design for a housing for power sweeper, as shown and described.
